UNITED STATES PATENT OFFICE.

EBENEZER HILL, JR., OF SOUTH NORWALK, CONNECTICUT.

IMPROVEMENT IN AIR-COMPRESSORS.

Specification forming part of Letters Patent No. **171,805**, dated January 4, 1876; application filed June 6, 1874.

To all whom it may concern:

Be it known that I, EBENEZER HILL, Jr., of South Norwalk, Fairfield county, and State of Connecticut, have invented a new and useful Improvement in Air-Compressors and Vacuum-Pumps; and I hereby declare that the following is a full, clear, and exact description thereof, reference being had to the accompanying drawings, making a part of this specification, and the letters of reference marked thereon, in which the same letter represents the same thing in each figure.

Figure 1 is a cut section of my improved compressor; Fig. 2, a plan view of the same.

The letters correspond to like parts in each view.

My invention relates to certain improvements in apparatus for compressing air, the object being to equalize the resistance of the air during the entire length of piston stroke, as will be hereinafter fully described; and it consists of two cylinders of different diameters, having pistons working upon the same piston-rod, and moving together in the same plane, the two cylinders being connected together by suitable valves or pipes, as will be hereinafter fully described. The air is driven at each stroke of the pistons from the large cylinder into the smaller one, where it is partially compressed, the return stroke further compressing the partially-compressed air, and forcing it out to point of consumption, as will be fully hereinafter set forth.

A description of the operation of the valves and mechanism upon one side of the piston will suffice to explain the whole, as the machine is double-acting, and the operation of the mechanism upon the other side of the piston is precisely the same.

H is a large cylinder; P, a smaller one, joined to H in the manner shown and herein described, The pistons L and K, being upon the same rod M, move together. While the pistons move from left to right the air is drawn into the space B of the cylinder H through the valve C. Upon the return stroke, from right to left, the air is forced by the piston L through the valve D, along the passage in the direction of the arrows, into the space E of the cylinder P. The cylinder P being smaller than H, a partial compression takes place when the air is forced in E. Upon the next forward stroke of the pistons, from left to right, the piston K compresses the air in E, and forces it through the valve F into the pipe G, the valve D closing meanwhile, from whence it is conducted off for use. During this same stroke the piston L inspires the air again through the valve C, and the operation is repeated, as above described.

Valves I, J, and N perform, respectively, the same offices as valves C, D, and F upon the other side of the pistons.

When deemed expedient a third cylinder can also be used with advantage.

What I claim is--

The combination of two communicating double-acting engines with cylinders of unequal diameters, their pistons mounted on the same rod and moving together, as described, to gradually compress the air, and equalize the resistance at the commencement and termination of the piston strokes, substantially as set forth.

EBENEZER HILL, JR.
